UNITED STATES PATENT OFFICE.

AXEL L. HANSEN, OF CHICAGO, ILLINOIS.

DRAG CHAIN.

Application filed June 15, 1921. Serial No. 477,712.

To all whom it may concern:

Be it known that I, AXEL L. HANSEN, a subject of the King of Denmark, but having declared my intention of becoming a citizen of the United States by taking out my first papers, residing at Chicago, in the county of Cook and State of Illinois, have invented a certain new and useful Improvement in Drag Chains, of which the following is a specification.

My invention relates to a conveyor chain, and particularly to a chain to be made of cast metal such as malleable iron, manganese steel, steel alloy, bronze etc., and is illustrated particularly in connection with a drag chain of the type which is dragged along a track or trough and has on it carrying elements, which engage and convey the material in the trough. Other objects will appear from time to time in the course of the specifications.

I illustrate the invention more or less diagrammatically in the following drawings wherein:

25 Figure 1 is a section through trough and chain illustrating the use of the chain;

Figure 2 is an elevation of a portion of the chain; with parts broken away and parts in section;

30 Figure 3 is a section on the line 3—3 of Fig. 2;

Figure 4 is a sectional showing of a variant type of chain;

Figure 5 is a detail section on the line 35 5—5 of Fig. 3;

Like parts are indicated by like symbols throughout the specification and drawings.

A is a trough supported in any framework B for example by the angle irons C to 40 which the trough is bolted. The trough is adapted to contain the materials to be conveyed such as ashes, for example, which are delivered to the trough by the spout D. The drag chain is an endless chain, as is usual in such installations, and is guided and propelled by the usual means, not shown, the portion of the chain not in contact with the material conveyed being carried on a return slide supported on the structural mem-

45 ber E and illustrated as comprising opposed rails FF supported on brackets or angle irons G supported on the framework B. The chain is composed of two types of link, namely, a single center link H which has projecting from each end of it, preferably cast integral therewith, a pair of pins

H', projecting from opposed sides of the link. This simple link element with its pins at either side, is gripped by the opposed heads I', of the opposed, joined, side link 50 heads I, each pair of which when secured together, forms a link element. The head portions I' have cast or otherwise formed therein, circular apertures I² adapted to receive the pins H' there being a rotatable 55 relation therebetween. Within the heads I' and penetrated by the apertures I² are the grease pockets I³ adapted to lubricate the bearing between the pin H' and the circular aperture I², entirely enclosed within the 60 head I'. The members I when fitted to the pins H' are secured together by any preferred fastening means for example the bolt K, and form the assembled link element. Integral spacing bosses L, preferably adjacent or about the bolt K, space the members I at the proper distance apart to prevent binding against the link H, and to 65 permit free rotation on the pins H'.

The space intermediate the links II is 70 bridged by the guards M in the form of flanges projecting across the opening between the two link members. The end surfaces N of the members I' provide bearing surfaces for the sprocket teeth J, which 75 form part of the chain actuating means not herein elsewhere illustrated and not part of this invention.

Intermediate the heads of the side link members, or at any preferred position thereon, are placed the conveying elements or members J', illustrated in Figures 1 and 2 as sidewardly projecting flanges adapted to contact the bottom of the trough in which the chain travels, and convey material there- 80 along. The space intermediate these conveying means and the heads I' is bridged by guards J² similar to the guards M.

Figure 4 illustrates a variant form of link and conveying member adapted for the conveying of logs and comprising a toothed member J¹⁰ which takes the place of the member J' as illustrated in Fig. 1. The log rests thereupon and the chain otherwise acts in the same way as the drag chain of Fig. 1, 85 save that the logs are carried by the chain about the upper portion of its excursion.

It will be realized that while I have shown a practical working embodiment of my invention, the size, shape and positioning 90 of the parts may be varied without departing from the spirit of my invention, and

particularly that the form of the chain may be widely varied to suit different types of conveying troughs or heads and to adapt it to convey different materials. The chain 5 is preferably cast of manganese steel but I do not limit myself to any method of manufacture or material. The conveying elements which the drawings show as integral with the double link elements could obviously be made integral with or be attached 10 to the single link element or to both link elements.

The use and operation of my invention are as follows:

15 I have illustrated a chain which is composed of a very small number of simple parts adapted particularly for use in a cast chain. The center link has cast on it a pair of opposed pins at either end. These pins form 20 the bearing surfaces which are engaged by sockets in the ends of said links, each pair of which forms a link element. These side link elements are properly spaced from each other by bosses and secured together adjacent 25 these bosses, after the sockets in the heads at either end of the side links have been fitted to the pins of the center link. Within the head of each side link member is a grease pocket which may be filled with 30 any suitable lubricant such as hard grease, graphite, etc. The materials carried, such as ashes, are prevented from slipping between the two side link members or from jamming in about the conveying members and the link 35 heads, by the guard plates which project across the top of the interval between them.

The form of the conveying elements is of course capable of infinite variation to suit the material conveyed. Where coal, ashes, 40 or similar finely divided materials are to be conveyed, the conveying element may be a paddle which contacts the bottom of the trough in which the chain travels, and sweeps or pushes before it the material there- 45 in contained or delivered. When logs are to be transported, elements with upwardly extending spikes or calks are provided to support the log and thus carry it forward. These illustrations are merely suggestions of 50 the many possible uses to which such a chain may be put. While I have described and shown my link members as having closed grease pockets, it will be realized that other lubricating means may be used and that 55 with some materials lubricating means may be entirely dispensed with. In such case the ends of the pins H' may, if desired, be permitted to project through the bearing heads of the double link members.

60 I claim:

1. A chain comprising a single link element, said link consisting of a single thickness of metal having opposed bearing pins formed on each side of each end thereof and 65 integral therewith, a plurality of centrally

restricted double link elements, bearing heads at each end thereof adapted to be secured to and rotatably to engage said pins, and conveying elements secured to said double link elements comprising lateral projections integral with said link elements. 70

2. A chain comprising a single link member having opposed bearing pins at either end thereof, and a plurality of double link elements adapted to be secured to and rotatably to engage said pins, and grease pockets lying within said double link elements 75 adjacent said pins.

3. A chain comprising a single link member having opposed bearing pins at either 80 end thereof, and a plurality of double link elements adapted to be secured to and rotatably to engage said pins, and grease pockets lying within said double link elements 85 adjacent said pins, said link provided with openings to said grease pockets, adapted to be closed by said bearing pins.

4. A link comprising opposed separate link elements, means for securing them together, and inwardly projecting guard members 90 adapted to substantially cover the interval therebetween.

5. In a chain, the combination of a single link element, having projecting bearing pins at either end with a double link element composed of a plurality of parts and contacted by said bearing pins, and grease pockets lying within said double link parts adjacent 95 said bearing pins.

6. In a chain the combination of a single 100 link element having projecting bearing pins at either end, with a double link element composed of a plurality of parts secured together about said pins, and an enclosed lubricant pocket lying entirely within each double link element, and adjacent said bearing surface.

7. In a link comprising opposed link elements, means for securing them together, 110 spacing means for properly spacing them, and inwardly projecting guard members adapted to substantially cover the interval between said elements.

8. In a link comprising opposed link elements, means for securing them together 115 and spacing means for properly spacing them comprising a plurality of opposed bosses adjacent the connecting means.

9. In a link comprising opposed link elements, means for securing them together 120 and spacing means for properly spacing them comprising a plurality of opposed bosses adjacent the connecting means, and inwardly projecting guard members adapted to substantially cover the interval between said elements.

10. In a link comprising opposed link elements, means for securing them together 125 and spacing means for properly spacing them, and means for substantially covering 130

the intervening portion between said links.

11. In a link comprising opposed link elements, means for securing them together and spacing means for properly spacing them, and means for substantially covering the intervening portion between said links, comprising integral guard plates bridging said intervening portion.

12. A chain comprising single link members having outwardly projecting integral bearing pins at the end thereof, and opposed link elements adapted to be positioned upon said bearing pins and to be secured together at a point removed from said bearing pins.

13. A chain comprising a single link member having opposed bearing surfaces at either end thereof, and a plurality of double link elements adapted to be secured to and rotatably to engage said bearing surfaces, and lubricating means lying within said double link elements, adjacent said bearing surfaces.

14. A chain comprising a single link member having opposed bearing surfaces at either end thereof, and a plurality of double link elements adapted to be secured to and rotatably to engage said bearing surfaces, and lubricating means lying within said double link elements, adjacent to and closed by said bearing surfaces.

15. A chain comprising a single link member having opposed bearing surfaces at either end thereof, and a plurality of double link elements, adapted rotatably to engage said bearing surfaces, and means for securing said double link elements together

against said bearing surfaces, and lubricating means adjacent said bearing surfaces, lying within said double link elements. 40

16. In a chain a link element and bearing surface thereon, a double link element adapted to engage it comprising a centrally constructed link body, a head portion at either end thereof, said head portion adapted rotatably to engage the single link element. 45

17. In a chain a link element and bearing surface thereon, a double link element adapted to engage it comprising a link body, a head portion at either end thereof, said head portion adapted rotatably to engage the single link element, and lubricating means enclosed within said head portion. 50

18. A chain comprising a single link member having opposed bearing surfaces at either end thereof and a plurality of double link elements adapted rotatably to engage said bearing surfaces, and means for securing said double link elements together 60 against said bearing surfaces comprising a bolt and adjacent spacing means therefor.

19. A chain comprising a plurality of link elements having inclosed bearing surfaces and grease pockets lying within said link elements and adjacent said bearing surfaces. 65

In testimony whereof, I affix my signature in the presence of two witnesses this 11th day of June 1921.
